UNITED STATES PATENT OFFICE

2,643,622

BLOWPIPE

Edward Meincke, Summit, N. J., and Hugh T. Smith, Chicago, Ill., assignors to Union Carbide and Carbon Corporation, a corporation of New York

Original application April 21, 1943, Serial No. 483,874. Divided and this application February 26, 1948, Serial No. 11,195

2 Claims. (Cl. 110—22)

1

This invention relates to blowpipe apparatus for thermochemically removing metal by a stream or jet of oxygen from metal bodies having a composition which resists the normal thermochemical action of a stream or jet of oxygen, such resistance being sufficient to hinder or substantially prevent such normal removal of metal. Examples of such metal bodies are ferrous metals, such as stainless steels, cast iron, and the like, and non-ferrous metals, such as copper, aluminum, nickel and various alloys. Such metal bodies are difficult or impossible to cut, deseam, desurface or the like by the normal impingement of a stream of oxygen upon successive portions heated to their ignition temperature. However, they can now be cut, deseamed, and desurfaced thermochemically by blowing into the reaction zone along with the oxygen jet a stream of powdered oxidizable adjuvant material, such as powdered iron.

Among the objects of the present invention are to provide blowpipe apparatus having means for rapidly starting and stopping the flow of finely-divided adjuvant powder to a thermochemical reaction zone; to provide blowpipe apparatus having means for automatically starting and stopping the flow of oxygen and powdered material in a predetermined sequential relation to one another; and to provide other features which will be apparent as the following description proceeds.

Apparatus constructed in accordance with this invention is illustrated in the accompanying drawings, in which:

Fig. 1 is a side elevational view, partly broken away and in section, of a blowtorch embodying the invention;

Fig. 2 is an enlarged longitudinal sectional view of the head end of the blowtorch shown in Fig. 1; and

Fig. 3 is a cross-sectional view taken along the line 3—3 of Fig. 2.

In the embodiment of this invention illustrated in Figs. 1, 2, and 3, a nozzle 11 is secured in a head 13 by an annular nut 15, in a well-known manner. The nozzle 11 has annularly arranged longitudinal preheat passages 17 for a combustible preheating medium, and a central longitudinal oxygen passage 19. Near the rear end of the nozzle 11 a series of ports 23 for powder are drilled transversely through the wall of the nozzle and the liner 21 to the oxygen passage 19. The ports 23 are located between the preheat passages 17, as shown clearly in Fig. 3, and are inclined forwardly toward the axis of the nozzle. An oxygen discharge tube 25, which has an annular flange adjacent to its rear end fitting snugly in

2

the rear end of the passage 19, is carried by the nozzle 11 and extends forwardly in spaced relation to the wall of the passage 19 to a point well ahead of the ducts 23 and spaced from the outlet of the passage 19. The front portion of the tube 25 carries a plurality of laterally extending fins 27 fitting snugly in the passage 19 and breaking down into a plurality of small ducts the annular space around the tube.

10 A combustible preheating medium, such as an oxyacetylene mixture, may be distributed to the passages 17 by an annular distributing chamber 31 supplied by a conduit 33 secured in a connecting bore 35 in the head 13.

15 Finely-divided adjuvant material may be supplied to the ports 23, and thence to the annular space 29, by a tube 37 secured in a connecting bore 39 leading into an annular chamber 41 surrounding a rear portion of the nozzle 11. A suitable source of powder, as shown in Fig. 1, may comprise a closed hopper 40 connected to the blowpipe by a flexible hose 42, and having an inlet pipe 44 through which gas under pressure may enter above the powder level.

20 Oxygen enters the discharge tube 25 through a conduit 43 secured in a bore 45 in head 13, and is then discharged into the relatively large passage 19, aspirating into the passage a plurality of small streams of powder flowing smoothly in substantially a straight line from the annular space 29.

25 The powder and oxygen mix intimately together while passing along the passage 19, and may be discharged against a body of metal preheated by the flames from the passages 17, thereby removing metal from the body thermochemically.

30 Adequate gas-tight seals preventing the passage of gas into or out of the annular chamber 31 are provided by two annular conical seats 46 and 48 on the rear end of the nozzle 11, which seat tightly on corresponding seating surfaces in the body 13.

35 It is desirable that powder from the passage 39 be controlled so as to enter the nozzle 11 only when metal-removing oxygen is flowing through the tube 25. This is accomplished by placing a suitable shut-off valve 47 in the bore 39 of the head 13. The valve 47 illustrated, by way of example only, is an ordinary rotatable plug valve secured in a cross bore 49 of the head 13 and having a through passage 51 which may be rotated into and out of register with the bore 39.

40 The valve 47 includes a stem 53 projecting from the side of the body 13 and engaging a crank 55 to which an operating rod or wire 57 is attached by a set screw. With this arrangement, the op-

erator of the blowpipe can start or stop the flow of powder to the nozzle 11 by manipulating the wire 57.

In Fig. 1 there is shown an arrangement whereby the operator may control in unison the flows of powder and metal-removing oxygen to the nozzle 11. The blowpipe handle 59 has the usual long lever 61, fulcrumed between its ends, and engaging at its rear end the stem 63 of a spring-closed valve controlling the flow of metal-removing oxygen to the nozzle 11. The lever 61 is connected through a suitable linkage 65 to the connecting rod 57, the construction and arrangement being such that when the operator actuates the lever 61 to start or stop the flow of oxygen, the powder control valve 47 is rotated to start or stop the flow of powder. The linkage may be such that the flows of oxygen and powder start and stop simultaneously, or any other predetermined sequential relation may be maintained.

The particular linkage 65 shown in Fig. 1, by way of illustration only, comprises a rotatable element 67 pivoted at 69 to a stationary support 71 within the handle 59. An L-shaped connecting link 73 is pivotally secured at one end to the element 67 on one side of the pivot 69, and at its other end to the valve-operating lever 61, whereby movement of the lever 61 causes the element 67 to turn through part of a revolution. A turn-buckle 75 is pivotally secured at one end to the element 67 on the opposite side of the pivot 69, and at its other end grips the connecting rod or wire 57, whereby rotation of the element 67 opens or closes the valve 47. A return spring 77 is secured at one end to the handle 59, and at its other end engages the pivoted element 67, for assisting the return of the lever 61 to its raised position when released by the operator, thereby closing the oxygen control valve 63 and the powder control valve 47.

This application is a division of our application Serial No. 483,874, filed April 21, 1943, Patent No. 2,444,900 granted July 6, 1948.

What is claimed is:

1. In a blowpipe having a handle, a head having a plurality of passages therein, a first conduit extending from a first one of said passages back through said handle for supplying gas to such first passage, and a second conduit in communication with a second one of said passages for supplying powder thereto; a first valve in said handle for controlling said first conduit; a second valve in said head for controlling said second conduit; a lever extending from said handle for

operating said first valve; reciproable valve actuating means extending from said handle to said second valve; and means linking said lever to said reciproable means whereby movement of said lever results in movement of said second valve.

2. A manually operable oxy-acetylene powder scarifying blowpipe comprising the combination with an oxy-acetylene deseaming torch including a tubular handle through which extend elongated conduits for conducting cutting oxygen and conducting a combustible gas mixture of oxygen and acetylene, manually operable lever means mounted on said handle for controlling the cutting oxygen delivered to the cutting oxygen conduit, a head connected to said conduits, and a nozzle connected to said head, said head having separate passages for conducting the cutting oxygen and the combustible gas mixture from such conduits to corresponding cutting and preheating gas passages in the nozzle; of a separate powder supply line extending through said handle and connected to said head, said nozzle having lateral ducts for conducting powder to the interior of the nozzle, and said head having an annular chamber communicating with such ducts, said head also having a powder passage connecting said powder supply line to said annular chamber, a powder valve mounted on said head for controlling the flow of powder supplied through said passage, and powder valve operating means comprising a flexible connecting rod operatively associated with said valve and said lever means, and spring means within said handle acting through said flexible connecting rod to close said valve.
